RHEOSTAT SWITCH

William O. Dennis, Kansas City, Mo.

Application October 27, 1936, Serial No. 491,627

5 Claims. (Cl. 200—92)

This invention relates to electric switches, and more particularly to an automatic rheostat switch adapted for remote operation in controlling electric circuits, for example, a circuit controlling a 5 slip ring induction type motor; the principal object of the invention being to provide a positively operated switch of simplified and compact construction for controlling of comparatively heavy electric currents.

10 Another object of the invention is to provide a switch wherein the operating mechanism may be readily removed from its panel for repairs or replacement without disturbing electrical connections or other wiring.

15 In accomplishing these and other objects of the invention, I have provided improved details of structure, the preferred forms of which are illustrated in the accompanying drawings, wherein:

20 Fig. 1 is a front elevational view of a rheostat switch constructed in accordance with my invention.

Fig. 2 is a vertical sectional view through the switch on the line 2—2, Fig. 1.

25 Fig. 3 is a diagrammatic view illustrating circuits for remotely controlling the switch, as connected in circuit with a slip ring induction motor.

Referring more in detail to the drawings:

The switch illustrated is particularly designed 30 for controlling operation of a three phase slip ring induction type motor and includes a fixed panel 1 preferably formed of insulating material, so that the contacts and other wiring for controlling a motor circuit may be directly mounted thereon, which, in the present instance, includes 35 three series of spaced contact plates designated 2, 3, and 4, and connected contact strips 5, 6 and 7, associated with the respective series of contacts for connecting resistance elements 10, 11 and 12 into the motor circuit as later described.

40 The contact plates of one series are mounted on the panel in alignment with the contact plates of each of the other series by screws 13 extending through the plates and into the panel. The contact strips are coextensive with the series of contact plates and are mounted on the panel by 45 screws 14 extending through the ends of the strips as shown in Fig. 1.

Supported adjacent the upper and lower edges of the panel and extending longitudinally of the 50 series of contacts are rails or tracks 15 and 16 preferably comprising rods having laterally bent ends 17 provided with shoulders 18 engaging the face of the panel and threaded terminals which extend through the panel and are secured there- 55 to by nuts 19 threaded on the extensions to draw

the shoulders tight against the face of the panel. The tracks 15 and 16 are thus spaced from the face of the panel by the lateral extensions 17 to accommodate switch mechanism now described.

Mounted on the tracks 15 and 16 and adapted 60 to move therealong over the contacts is a carriage 20 preferably comprising a rectangular plate 21 of insulating material extending from the top to the bottom of the panel, as best illustrated in Fig. 1. Rotatably mounted on the lower ends of 65 the plate are grooved rollers 22 adapted to bear on the upper side of the track 16, and fixed to the rear of the plate at its upper end are rearwardly extending brackets 23 carrying grooved rollers 24 for engaging the rear face of the track 70 15, as illustrated in Fig. 2. The carriage, including the plate 21, is thus mounted for rolling movement on the tracks and may be readily detached therefrom by raising the lower end of the plate to remove the rollers 22 from engagement 75 with the lower track 16, after which the rollers 24 may be unhooked from the upper track 15.

Supported on the rear side of the plate 21 by posts 25 and 26 is a brush-supporting bar 27 extending laterally across the series of contacts 80 and contact strips, as shown in Fig. 2. The strip 27 is formed of insulation material and is provided with pairs of brushes 28 adapted to move over the series of contacts 2, 3 and 4 at each side of the screws 13, and with brushes 29 85 adapted to move along the contact strips 5, 6 and 7. The pairs of brushes 28 are interconnected by flexible leads 30 and are also connected with their related brush 29 by a flexible lead 31, so that the brushes for each series of contacts and 90 its contact strip are electrically connected whereby the series of contacts are in circuit with their related contact strips.

The brushes 28 and 29 may be of any suitable construction but are preferably mounted for 95 yielding contact on the plates by springs 32 coiled about pins 33 supported by the bar 27, one end of the spring engaging a brush and the other end bearing against the strip 27, as illustrated in Fig. 2.

In order to move the carriage over the contacts, a motor 34 is mounted on the front side of the plate 21 by screws 35 extending through a flange 36 on the motor and into the plate.

The armature shaft 37 of the motor extends 105 through a bearing opening 38 in the plate and carries a pinion 39 meshing with a chain of reduction gearing designated 40 for actuating a gear 41 fixed on a shaft 42 projecting from the rear face of the plate 21, and which meshes with a 110

rack bar 43 fixed to the front side of the switch panel adjacent the lower track 16. Thus it is apparent that when the motor 34 is energized, the pinion 39 will actuate the transmission gearing 5 40 to rotate the gear 41 and cause it to roll along the rack bar to move the carriage on the tracks 15 and 16 and connect the contact plates in series with their respective contact strips, thereby cutting out resistance in the motor circuit or 10 adding resistance, depending on the direction of travel of the carriage.

In order to stop the motor and prevent coasting of the armature when the motor circuit is broken as later described, I provide the armature 15 shaft 37 with a cone-shaped disk 44 which is normally urged into braking engagement with a complementary-shaped brake flange 45 fixed to the plate 21 by a coil spring 46 sleeved on the armature shaft and having one end bearing against 20 the pinion 39 and its opposite end against the motor carriage plate 21, so that when the brake disk is in engagement with the fixed member 45 the spring 46 draws the armature of the motor from the center of its field and when the 25 circuit to the motor is again closed, energization of the motor field will cause shifting of the armature to release braking action of the disk 44.

Supported by the carriage plate 21 above the motor is a reversing switch indicated in Figs. 1 30 and 2 by the housing designated 47 in Figs. 1 and 2, whereby the current through the armature may be reversed to change direction of rotation of the motor and consequently direction of travel of the carriage. The switch 47 preferably includes a bell crank lever 48 (Fig. 3) pivotally mounted by a pin 49 on the front face of the plate 21, and having an upwardly projecting arm 50 provided with mercury tube switch receiving seats 51 and 52. The other arm of 35 40 the bell crank lever 53 is connected by a link 54 with an arm 55 of a second bell crank lever 56 pivotally mounted by a pin 57 projecting from the plate at a point below the pin 49 which mounts the bell crank lever 48.

45 The other arm 58 of the second bell crank lever 56 depends downwardly and carries a weighted armature 59 operable between a pair of electromagnets 60 and 61. The magnets 60 and 61 include U-shaped pole pieces 62 and 63 having magnet coils 64 and 65 so that when the magnet 64 is energized as later described, the armature 58 will be drawn toward the magnet 60 to swing the bell cranks in one direction, and when the other magnet is energized the armature will be 50 55 actuated to move the bell cranks in the opposite direction for closing and opening circuits to the carriage actuating motor 34 as now described.

Supported in the seats 51 and 52 are mercury tube switches 66 and 67, each having a central pocket 68 for retaining a quantity of mercury 69 when the mercury tube switches are in horizontal position, i. e., when both magnets are deenergized and the armature 59 depends by gravity between the magnets 60 and 61, at which point all circuits to the actuating motor are open, the mercury being adapted to flow from the pockets to close the circuits when either of the coils is energized.

The mercury tube switch 66 is provided in its opposite ends with pairs of terminals 70-71 and 72-73, and the mercury tube switch 67 is also provided with similar terminals 74-75 and 76-77, which terminals 70-71 and 74-75 are adapted to be connected by the mercury to close circuits to operate the motor in one direction, and the terminals 72-73 and 76-77 are adapted to

reverse the current to operate the motor in the opposite direction as now described.

Fixed to the switch panel and extending parallel with the contacts previously described are laterally spaced contact strips 78, 79, 80 and 81 80 for conveying current to the actuating motor 34 and the magnet coils through brushes 82, 83, 84 and 85, respectively, which are carried on the bar 27 similarly to the brushes previously described.

86, 87 and 88 designate the line wires of a 85 three phase electric circuit and connected with the line 87 is a wire 89 for supplying current to the contact strip 81 and through the strip to the brush 85 connected by a wire 90 with the terminals 75 and 76 of the mercury tube switch 67, 90 the wire 90 being connected in series with one of the windings 91 of the carriage actuating motor 34.

Connected with the supply line 86 is a conductor 92 for adapting completion of the circuit 95 through the contact strip 78, brush 82 and a conductor 93 connecting the terminals 71 and 72 of the other mercury tube switch 66.

The terminal 70 of the mercury tube switch 66 and the terminal 77 of the mercury tube switch 100 67 are connected together by a conductor 94 which is connected to one of the brushes of the motor 34 by a conductor 95. The remaining terminal 73 of the mercury tube switch 66 is connected by a conductor 96 with the remaining 105 terminal 74 of the mercury tube switch 67 which in turn is connected to the other brush of the motor 34 by a conductor 97.

Thus when the mercury tube switches are tipped to the right (Fig. 3), the mercury closes 110 circuit through the terminals 72 and 73 of the mercury tube switch 66 and through the terminals 76 and 77 of the mercury tube switch 67 thereby completing circuit from the line wire 87 through conductor 89, contact strip 81, brush 115 85, conductor 90, field winding 91, terminals 76 and 77, conductor 95, armature of the motor 34, conductor 97, terminals 72 and 73 of the mercury tube switch 66, line 93, the other field winding 98 of the motor 34, brush 82, contact strip 78, line 120 wire 92 to the feed line 86, energizing the motor to move the carriage over the series of contacts 2, 3 and 4 to cut out resistance elements 10, 11 and 12.

The motor 34 will continue to move the carriage across the contacts until all of the resistances are out of circuit, at which point the motor may be reversed by tipping the mercury tube switches in the opposite direction to break the circuit through the terminals 72-73 and 76-77 130 and establish circuit through the terminals 70-71 and 74-75, reversing direction of current through the armature of the motor 34 to cause the motor to rotate in reverse direction and return the carriage over the contacts to again cut 135 in the resistances, the circuit being then completed through the line 89, brush 85, conductor 90, armature winding 91, mercury tube switch terminals 75 and 74, line 97, motor armature 34, conductor 95, terminals 70 and 71, conductor 140 93, field winding 98, brush 82, conductor 92 to the lead line 86, thus reversing direction of flow through the motor armature 34.

In order to energize the solenoids 64 and 65 remotely of the switch for effecting operation of 145 the mercury tube switches, I provide push buttons 99 and 100 connected in circuit to the magnets through the bars 79 and 80, as now described.

The push button 99 is for operating the solenoid 64 to move the carriage to the right in cut- 150

ting out the resistances and closes circuit through the conductor 92, a conductor 101 connecting the push button with the wire 92 and the push button with the contact strip 79 to supply current to the brush 83 which is connected to the coil 64 by a conductor 102. The other lead of the coil 64 is connected by a conductor 103 with the conductor 90 to complete the circuit.

The push button 100 is also connected to the conductor 92 and to the contact strip 80 by a conductor 104 supplying current to the brush 84 which is connected to one of the leads of the coil 65 by conductor 105 and the other lead of the coil is connected to the conductor 103 to complete the circuit for that coil.

In order to stop movement of the carriage when it approaches the right hand end of the switch panel, the contact strip 79 terminates short of the other contact strips to break the motor circuit when the brushes operating on the series of contacts are moved onto the last contact, at which point all of the resistances are out of circuit.

In order to stop movement of the carriage in the opposite direction the contact strip 80 is shortened in like manner, and in order to prevent misalignment of the brushes I provide dead contacts 105 and 106 at the terminals of the strips to retain the brushes in position.

The resistances of a switch constructed as described are connected together at their left hand ends and the other ends are connected respectively by leads 107, 108 and 109 with the armature terminals of a slip ring motor which is to be controlled by the switch, and which is designated 110 in the drawings, the field winding of the motor being supplied from the wires 86, 87 and 88.

In operating a switch constructed and assembled as described, assuming that the carriage is positioned at the left hand side of the switch panel with all of the resistances in circuit, the operator will close the circuit to the magnet coil 64 by pushing the button 99 so that a circuit is completed from the lead line 86, conductor 92, push button 99, contact strip 79, brush 83, conductor 102, magnet 64, conductors 103 and 90, brush 85, contact strip 81, conductor 89 to the other line wire 87.

Energization of the coil 64 attracts the armature 99 of the magnet to cause the bell crank levers 48 and 56 to tip the mercury tube switches and close circuit between the terminals 72-73 and 76-77, thereby energizing the motor 34 to move the carriage across the contacts, the circuit being established through the lead line 86, conductor 92, contact strip 78, brush 82, conductor 93, motor winding 98, terminals 72-73, conductor 96, motor armature, conductor 95, terminals 77 and 76, conductor 90, field winding 91, brush 85, contact strip 81, conductor 89, and lead line 87.

The carriage will continue to move across the contacts until the brush 83 rides off the contact strip 79 or until the operator breaks the circuit by removing his finger from the push button 99, movement of the carriage gradually cutting out the resistance from the motor circuit until the motor is operating at its maximum or an intermediate speed selected by the operator.

Breaking of the circuit by the push button 99 will cause deenergization of the magnet coil 64 to permit the armature 58 to swing away from the magnet field pole pieces 60, thereby swinging the mercury tube switches into horizontal position to break circuit between the mercury tube switch terminals to effect deenergization of the

motor windings 91 and 98, whereupon the spring 46 will draw the armature of the motor out of alignment with the center of the field winding and cause engagement of the brake disk 37 with the brake band 45 to prevent coasting of the carriage over the selected contacts.

If the operator then desires to increase the speed of the motor he will again close circuit through the push button 99 to continue forward travel of the carriage, but should he desire to reduce the speed of the motor he will close circuit through the magnet coils 65 by operating the push button 100 which establishes circuit through the conductor 92, conductor 104, contact strip 80, brush 84, conductor 105, magnet coil 65, conductor 103, brush 85, contact strip 81, conductor 89, the line wire 87.

Energization of the coil 65 causes the pole pieces of the magnet 61 to attract the armature, thereby swinging the mercury tube switches in reverse direction to close circuit through the terminals 70-71 and 74-75. Circuit is then established through the motor 34 with the current flowing in through the armature in reverse direction, to reverse direction of rotation, thereby bringing more of the resistances into the circuit wires 107, 108 and 109, the circuit to the motor 34 being established through conductor 92, contact strip 78, brush 82, conductor 93, field winding 98, terminals 71-70, conductor 94, conductor 95, motor armature, conductor 97, terminals 74-75, conductor 90, field winding 91, brush 85, contact strip 81, conductor 89, and lead line 87.

When the motor has been reduced to the desired speed the operator will remove his finger from the push button 100 to break circuit to the magnet coil 65, allowing the mercury tube switches to return to normal position and breaking circuit to the terminals 71-72 and 74-75, thereby stopping operation of the motor 34.

Attention is directed to the fact that as soon as circuit is established through the motor field windings 91 and 92, the armature of the motor will be drawn into the center of the field to release the brake elements to permit rotation of the motor, but when the circuit is interrupted to the field windings the spring 46 will again apply the brake to stop rotation of the motor and prevent coasting of the carriage over the selected contacts.

While I have described the invention as being employed in connection with a slip ring induction type motor, it is apparent that a switch constructed as described may be used for controlling any circuit wherein a rheostat switch is employed, and I do not wish to be limited to the specific arrangement described.

What I claim and desire to secure by Letters Patent is:

1. In a rheostat switch of the character described, a panel having a series of electric contacts and a cooperating contact strip extending across its face, rails extending longitudinally of the panel adjacent opposite side edges thereof, a circuit closing unit mounted on the rails and movable across the contacts including a carriage, means on the carriage controlling circuits through said contacts and contact strip, a motor on the carriage and operable to move the carriage along said rails, and a reversing mechanism on the carriage controlling the motor.

2. In a rheostat switch of the character described, a panel having a series of electric contacts and a cooperating contact strip extending

across its face, rails extending longitudinally of the panel, a carriage removably mounted on the rails, means on the carriage controlling circuits through said contacts, a motor on the carriage and operable to move the carriage along said rails, a reversing mechanism on the carriage for controlling the motor, contact strips on the panel supplying current to said motor, and brushes on the carriage contacting said strips and operably wired to said reversing mechanism and said motor so that the carriage and its operating mechanism are removable as a unit for replacement with another unit without affecting the wiring.

3. A rheostat switch, a panel having electric contacts extending across its face, rails extending longitudinally at the top and bottom of the panel, a carriage movable over said contacts, rollers operable on said rails to support the carriage, means on the carriage controlling circuits through said contacts, a motor on the carriage operable to move the carriage along said rails, a reversing mechanism on the carriage for controlling the motor, contact strips on the panel supplying current to said motor, and brushes on the carriage contacting said strips and operably wired to said reversing mechanism and said motor so that the carriage is removable from the rails without affecting the wiring.

4. A rheostat switch, a panel having electric contacts extending across its face, rails extending across the top and bottom of the panel, a carriage removably mounted on said rails, means on the carriage controlling circuits through the

contacts, a rack bar on the panel and extending longitudinally of the rails, a motor on the carriage, means gearing the motor to said rack bar for moving the carriage along the rails, reversing mechanism on the carriage for controlling the motor, contact strips on the panel supplying current to said motor, and brushes on the carriage contacting said strips and operably wired to said reversing mechanism and said motor so that the carriage is removable from the panel without affecting the wiring.

5. A rheostat switch, a panel having electric contacts extending across its face, rails extending across the top and bottom of the panel, a carriage removably mounted on said rails, means on the carriage controlling circuits through the contacts, a rack bar on the panel and extending longitudinally of the rails, a motor on the carriage, means gearing the motor to said rack bar for moving the carriage along the rails, reversing mechanism on the carriage for controlling the motor, contact strips on the panel supplying current to said motor, brushes on the carriage contacting said strips and operably wired to said reversing mechanism and said motor so that the carriage is removable from the panel without affecting the wiring, and braking mechanism associated with said gearing and operable automatically upon operation of the reversing mechanism to prevent coasting of the carriage on the rails.
